UNITED STATES PATENT OFFICE

2,405,584

SYSTEM OF BUILDING CONSTRUCTION

Harlow Lewis, Provincetown, Mass.

Application February 13, 1945, Serial No. 577,718

3 Claims. (Cl. 20—2)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to building construction and has for its objects generally to improve and simplify the construction of floor, wall, partition and roof systems in structures of various types; to provide connections at horizontal, vertical and oblique joints which will give the maximum of rigidity and stiffness to the structure and which will permit a more positive securing of the various members together; to provide a simple and inexpensive system of construction which will reduce the amounts of material and labor required for the erection of structures; to provide a novel method for combining in one structural unit the function of joists, bridging, and underflooring; rafters, bridging and roof sheathing; and studs, bridging, sheathing and finish; to provide a novel construction unit which will permit the framing and enclosing of floors, walls, roofs and partitions in one operation; to provide a structural unit by which the maximum load may be carried by a simple method of construction at the minimum expense; to provide a novel form of interlocking joints for the connection of the main members of a structure; to provide a system of construction which will decrease the height required for the exterior walls of a building; to provide a novel construction unit and a system of framing which will materially decrease the weight of the structural elements; to provide a novel construction unit and system of construction which may be erected and assembled by workmen less skilled in the art than those usually employed; to provide a novel construction unit and system of construction whereby an extremely strong and rigid lightweight structure may be speedily and cheaply erected without the need for highly skilled labor; to improve and simplify construction, decrease the time and labor required to erect a building, decrease requirements for construction material in construction and increase the efficiency of the structure.

A further object of the invention is to make possible a novel system of construction whereby several structural elements which heretofore have had to be assembled in three or more operations—as for example, floor joists, bridging and underflooring in floor construction, rafters, bridging and sheathing in roof construction, studding, bridging and finish in partition construction, and

2

studding, bridging, sheathing, and finish in exterior wall construction, may now be combined in one.

With these objects in view, the invention consists of the construction unit of a modified U section, formed of any laminated or sheet material, with or without metal reinforcement, so as to permit automatic locking and bracing in any position when framed in combination with one or more similar units and accessories.

The invention further consists in having the legs of the units formed with flanges parallel to the opposite face, thereby obtaining greater stiffness and load carrying capacity, and a larger surface for the attachment of finish, equipment, or the like.

The invention further consists in forming the units so as to meet all structural requirements without resort to specially fabricated connections.

The invention further consists in the novel construction system which permits the framing of these units together in such a manner as to form at once and in one operation, an enclosed structure with continuous floor, wall and roof surfaces, as well as supporting members, these continuous surfaces being ready to receive the finish or, if preferred, to act themselves as finished surfaces for walls, ceilings and partitions.

Referring to the accompanying drawings:

Fig. 1 is a fragmentary perspective view illustrating the relative positions of the structural members in assembled positions.

Fig. 2 is an elevation partly in vertical section.

Fig. 3 is a fragmentary transverse vertical sectional view taken on line 3—3 of Fig. 2.

Fig. 4 is a fragmentary perspective view of the end portion of a horizontal floor unit.

Fig. 5 is a cross-sectional view of the preferred form of the building unit.

Fig. 6 is a modification of the same, and

Fig. 7 is a perspective view of a pair of the construction unit cleats.

Like numerals of reference indicate the same parts throughout the several figures, in which:

1 indicates the building unit which may be of any laminated sheet or other suitable material, which as shown in Figs. 5 and 6 is of modified U-form having a flat central web portion 2 and two depending side members 3 which terminate in outwardly extending flanges 4 parallel with the central web portion 2. These side members 3 have their portions 5 which are immediately adjacent the central web 2, formed at right angles to the central web 2 and the balance 6 of the side members converge toward each other to the point

where they merge into the outwardly extending flanges 4 as shown in the drawings. It will be noted from Figs. 5 and 6 that the flanges 4 of the units 1 do not extend laterally beyond the surface of rectangular portions 5 of the side members 3 so that when two of the units are assembled together in the same plane the rectangular portions 5 and the side edges of the flanges 4 of two assembled units abut each other.

Referring now to Fig. 1, it will be seen that the vertical units 1 abut one another to form a continuous wall between floors, and there is provided on top of the assembled wall units 1, a flat horizontal member 7. On the under surface of the horizontal member 7 and conforming to the internal shape of the wall units, is a pair of cleats 8 for each unit which are fastened to the horizontal member in any approved manner, as by nails 9, as shown in Fig. 3. By means of these cleats 8, the assembled wall units 1 are 10 20 securely locked against displacement.

Referring now to the horizontal floor units 4, it will be seen from Fig. 4 that their end portions 10 are formed with diverging side edges 11 to conform to the interior formation of the wall units 1, as heretofore described, and as shown in Figs. 5 and 6, so that when the end portions 10 so formed, are inserted into the interior of the vertical wall units 1, and rest flatly on the horizontal member 7, an interlocking joint is established between the vertical units and the horizontal floor units. To effect the joint, the side members 3 of the floor units 4 are cut away, as shown in Fig. 4, to form vertical abutments 12 on each floor unit 4 to abut against the horizontal member 7. When the floor units 4 are assembled in this manner, a continuous floor surface is formed, as shown in Fig. 1.

For the ceiling units under and supporting the roof members, the end portions of said units are not formed with diverging side edges, but the side members 3 of each unit are cut away to provide abutments 12 to abut against the horizontal member 7, and the end of each horizontal unit 4, is formed upwardly to form an abutment 13 for the ends of the roof units 1. These roof units 1 are assembled to form a continuous outer surface and have their lower ends beveled at 14 to seat on the horizontal ceiling units 4 and to engage the upstanding abutments 13 of the horizontal ceiling units.

It is apparent that the wall units may be sheathed or otherwise processed or treated to form any finish desired, while the floors, ceilings and roof may be covered in any suitable manner and with any suitable material, so as to present any finish desired.

Having thus described the invention, I do not wish to be understood as limiting myself to the exact construction as shown and described, as I consider myself clearly entitled to all such changes and modifications as fall within the limit and scope of the appended claims.

I claim:

1. A system of building construction which includes a plurality of vertical wall, horizontal floor and pitched roof units of modified U section, each unit having a central web portion and two side members, the portion of each side member directly adjacent the central web portion of the unit being disposed at right angles to the central web portion, the next adjacent portions of

the two side members converging toward each other, a flange formed at the termination of each side member and extending outwardly therefrom so that the lateral edge of each flange 5 lies in the same plane as the outer surface of the rectangular portion of each side member, whereby the rectangular portions of the side members and the lateral edges of the flanges of two units will abut each other when the two units are assembled together, the end portions of the horizontal floor units being adapted to enter within the vertical wall units and shaped to conform to the said converging side members thereof to lock the ends of the horizontal floor units within the interiors of the vertical wall units.

2. A system of building construction which includes a plurality of vertical wall units, a plurality of horizontal floor and ceiling units and a plurality of roof units, each of said units being of a modified U section, each unit having a central web portion and two side portions converging toward each other, a flange at the termination of each side portion and extending outwardly therefrom so that the lateral edge of one flange will abut against the lateral edge of another flange when two of the units are assembled together, a horizontal member positioned on the ends of the vertical wall members, means on the horizontal member for effecting an interlocking engagement with each vertical wall unit, the vertical wall units above said horizontal member being adapted to rest on said horizontal member, the end portions of the horizontal floor units being shaped to conform to the converging side portions of the vertical wall units resting on the said horizontal member, the said formed end portions being also adapted to rest on the said horizontal member, and to form interlocking engagement with the vertical wall units, and to provide an abutment for engagement with the said horizontal member.

3. A system of building construction which includes a plurality of vertical wall units, a plurality of horizontal floor and ceiling units and a plurality of roof units, each of said units being of a modified U section, each unit having a central web portion and two side portions converging toward each other, a flange at the termination of each side portion and extending outwardly therefrom so that the lateral edge of one flange of one unit will abut against the lateral edge of a flange of an adjacent unit when two of the units are assembled together, a horizontal member located on the top ends of the vertical wall units adjacent the roof units, said horizontal member including means which enter within the ends of the wall units for cooperation with the said converging side members of the wall units for retaining the said horizontal member in fixed operative position, the end portions of the horizontal floor and ceiling units being shaped so that the central web portions thereof rest upon the said horizontal member and the converging side portions thereof form a vertical abutment for the said horizontal member, the said roof units having their ends beveled to rest upon the said horizontal member, and an abutment formed on the end of the floor and ceiling units for engagement with the ends of the roof units.

HARLOW LEWIS.
